UNITED STATES PATENT OFFICE.

GEORGE H. FOX, OF BANGOR, MAINE; ANNA B. FOX ADMINISTRATRIX OF SAID GEORGE H. FOX, DECEASED.

MACHINE FOR MOLDING CANDY PIPES AND OTHER ARTICLES.

978,726.

Specification of Letters Patent. Patented Dec. 13, 1910.

Application filed March 1, 1910. Serial No. 546,659.

To all whom it may concern:

Be it known that I, GEORGE H. FOX, a citizen of the United States of America, residing at Bangor, in the county of Penobscot, 5 in the State of Maine, have invented certain new and useful Improvements in Machines for Molding Candy Pipes and other Articles, whereof the following is a specification.

This invention relates to a machine especially adapted for the manufacture of imitation smoking pipes made from candy.

The principal object of the invention is to provide a simple machine for the economical production of toy candies of the character 15 indicated.

Figure 1 of the accompanying drawings represents a front elevation of one embodiment of this machine in open position. Fig. 2 represents a side elevation thereof, parts 20 being broken out for better illustration. Fig. 3 represents in part a side elevation and in part a vertical transverse section thereof in closed position. Fig. 4 represents a vertical transverse section of the plunger part 25 of the mold. Fig. 5 represents a perspective view of a toy pipe made by this machine. Fig. 6 represents a side elevation of another form of actuating mechanism in which the treadle lever is provided with a weighted 30 arm for restoring it to normal position in lieu of the springs in the head for that purpose. Fig. 7 represents an end elevation of the hinged jaw provided with a cam of another form adapted to restore the jaw to normal position whereby the spring for that 35 purpose is dispensed with. Fig. 8 represents a vertical section through one of the guideways of the head and an end elevation of a plunger carrier having its slide rod of a diameter to fit said guideway, the spring of the 40 other construction being dispensed with and the guideway being practically closed by the slide rod whereby entrance of candy is prevented.

45 The same reference numbers indicate corresponding parts in all the figures, round numbers being used for the principal elements and intermediate numbers for the attributes thereof respectively.

50 The frame of this machine comprises a head 10 having a rearward horizontal flange 11, dependent hangers 20 and 25 extending downward from said head and preferably integral therewith and horizontal arms 30 and 35 extending rearward from the lower

ends of said hangers and also preferably integral therewith. The head is provided on its front face with two ears or perforated lugs 12 and 13 and with a mold segment 15, preferably of brass, set in a recess or otherwise fixed in said face. Said front face is also provided with a flaring guide recess 14 tapered to a small orifice which extends through the side wall of said mold segment and which opens into the mold near the bottom thereof. The head 10 is also provided with two vertical holes or guideways 16 and 17 which extend through said head and are provided with internal shoulders 18 and 19.

The hangers 20 and 25 are provided on 70 their inner faces near their lower ends with side lugs 21 and 26 having guide holes 22 and 27 which are in alinement with the guide holes 16 and 17. The rearward arms 30 and 35 are provided respectively at their 75 inner ends with pintle holes 31 and 36 disposed opposite each other. These arms are also provided with another set of similar pintle holes 32 and 37.

The machine is secured to a bench or table 80 A by means of bolts 23 and 24 passing through the horizontal flange 11 and through said table and by braces 28 and 29 connected at their outer ends by bolts 33 and 34 with the arms 30 and 35 and at their 85 inner ends by bolts as 39 with the under side of said table.

A movable hinged jaw 40 swings on a pivot rod 41 supported in the lugs 12 and 13. This jaw is provided with a mold segment 90 45 disposed in a recess in its inner face and adapted to coöperate with the mold segment 15 in the head 10 and form therewith a mold open at the top and approximately in the shape of a bowl of a tobacco pipe. This 95 mold segment may be of brass or other suitable material. This segment is also provided on its inner face with a lateral opening 42 adapted to register when the mold is closed with the orifice of the guide recess 14. 100 The hinged jaw 40 is provided on its outer face with clamping screws 43 and 44 disposed one above the other. The hinged jaw is also provided on its opposite sides near its top with laterally projecting lugs 46 and 105 47 having rounded corners 48 and 49.

A plunger carrier 50 is supported at the upper end of a vertical sliding frame comprising rods 60 and 65 extending through the guideways 16 and 17 of the head 10 and 110

through the guide holes 22 and 27. The plunger carrier is provided with dependent lugs 51 and 52 adapted to engage the lateral lugs 46 and 47 of the hinged jaw 40 for 5 tightly closing the hinged jaw and pressing the mold sections together. These dependent lugs are preferably beveled at their lower ends at their inner faces to facilitate engagement with said lateral lugs.

10 A plunger 55 constructed of brass or other suitable material is secured to the under side of the carrier 50 opposite the top opening of the mold. This plunger is preferably of a rounded acorn-like shape adapted to co- 15 operate with the mold in forming the bowl of a pipe. This plunger is secured to the plunger carrier by any suitable means. In the form illustrated the plunger is provided with a threaded shank 56 which engages a 20 screw-threaded hole in the center of the plunger 50, and with a flange 57 which is seated against the under face of the plunger carrier. This flange is of a diameter to fit within and practically close the mold and 25 is provided on its under side with a groove 58 as shown in Fig. 4. On the depression of the plunger the flange enters the top of the mold and crowds down the soft candy and the groove 58 finishes the top of said 30 pipe bowl, forming a rounded surface thereon. A nut engages the projecting end of the threaded shank 56 on the upper side of said carrier.

The slide rods 60 and 65 are screw- 35 threaded near their lower ends and the rod 60 is provided with a pair of clamping nuts 62 and 63 and the rod 65 is provided with a pair of clamping nuts 67 and 68. The slide rods 60 and 65 are fixed at their upper 40 ends in socket holes of the plunger carrier 50 or otherwise secured thereto. Springs 61 and 66 surround said slide rods between the plunger carrier 50 and the shoulders 18 and 19 of the head 10. These springs or 45 their equivalents serve to hold the plunger carrier normally in elevated position out of engagement with the hinged jaw 40. A cross head 70 is secured to the lower ends of said rods by means of said nuts. This cross head is preferably provided with an anti- 50 friction roller 71.

An intermediate cross head 75 is secured to said slide rods between the head 10 and the side lugs 21 and 26. This cross head is 55 preferably adjustable on said slide rods by set screws 76 and 77 or other means and is preferably provided with an antifriction roller 78.

A cam arm 80 connected with the hinged 60 jaw 40 is engaged by the cross head 75 to operate said jaw for closing the mold. The shank of this cam arm is provided with slots 81 and 82 and the clamping screws 43 and 44 pass through said slots and serve as 65 means of attachment for said cam arm and

render the same adjustable on said jaw. The cam arm projects downward from said jaw, thence curves inward forming a curved cam face 85 and thence extends downward in a straight cam face 86. In the normally 70 open position of the mold, the cross head 75 rests in the recessed or curved cam face 85 and thence as the slide frame descends said cross head rides over the inward curve and swings the hinged jaw 40 into closed 75 position and thence rides down the straight cam face 86 during the downward movement of the plunger carrier and plunger. The spring 87 is connected at one end with the inner end of the cam arm and at the other 80 end with a cross bar 88 spanning the space between the braces 28 and 29. This spring operates to swing the hinged jaw into open position and to normally hold it there.

A pintle 90 in the form of a rod or shaft 85 is supported in the pintle holes 31 and 36 (or the pintle holes 32 and 37) or other bearings of the horizontal arms 30 and 35. An actuating lever 95 preferably a foot lever having a treadle 96 is supported on said 90 pintle. This lever is provided with an arm 97 which engages the cross head 70 of the sliding frame. This arm is preferably provided with a slot 98 so as to have a bearing against both the upper and under sides of 95 said cross head or of its antifriction roller.

In Fig. 6 the actuating mechanism is shown in a modified form whereby the springs 61 and 66 of the head may be dispensed with. In this case the treadle lever 100 95 is provided preferably near its upper end with a lateral arm 110 carrying a weight 111 adjustable thereon by means of a set screw 112 or otherwise. This weighted arm operates to swing the lever 95 into normal position and open the mold.

In Fig. 7 a supplemental arm 83 of a form similar to the cam arm 80 is secured at one end to the jaw 40 between it and the cam plate 80 by the same bolts which secure said plate 80 and at its opposite end the cam arm 83 is secured to the cam 80 by a bolt connection 89. This cam arm 83 has a cam surface 84 and the space between said cam arms 80 and 83 forms a cam way in 110 which cross head 75 travels during the swing of the actuating lever in either direction. When the lever is swung forward, the slide rods 60 and 65 are lifted carrying upward 115 the crosshead 75 and the plate 83 engaged by said crosshead operates to open the mold. In this construction the spring 87 can be dispensed with. This supplemental cam spring or cam arm covers and protects the antifriction roller from particles of candy 120 which might otherwise drop upon it.

In Fig. 8 the slide rods as 65' which support the plunger carrier are shown of a diameter adapted to fit and fill the guideways 125 in which they travel, the springs for lifting

the carrier being unnecessary in view of the modifications just above described. The filling of the guideways by the slide rods prevents particles of candy from falling into 5 and clogging said guideways.

A pipe 100 comprising a candy bowl 101 and a wooden pipe stem 102 is made by this machine.

The operation of the machine will now be 10 described.

A candy composition known as hard candy in a warm plastic state is employed in making these articles. The mold sections 15 and 45 are preferably dusted with powdered sugar, fine flour or other suitable lubricant to prevent adhesion thereto of the candy material. The machine being in open position as shown in Figs. 1 and 2, a roll of such candy material about one and one-half 20 inches long and three-fourths of an inch in diameter, more or less, is placed in one of the mold sections. The treadle lever 95 is then pushed backward. In this movement of the lever, the cam arm 97 engaging the 25 cross head 70 of the sliding frame 60-65 swings downward and pulls down said frame. The intermediate cross head 75 on said frame engaging the cam arm 80 attached to the hinged jaw 40 swings said 30 jaw into closed position and the mold section 15 shuts against the mold section 45 and presses said candy roll approximately into the form of a pipe bowl. One end of a pipe stem or "sucker stick" 102 is pushed 35 through the flaring guide groove 14 of the head 10 and the lateral opening 42 of the hinged jaw into the mold, where it penetrates and is surrounded by the candy material. A further movement of the actuating 40 lever 95 brings down the plunger carrier 50 and causes the plunger 55 thereon to enter the top of the mold and form the hollow space in said bowl. The plunger presses the candy material closely against the walls 45 of the mold and around the end of the sucker stick and completes the shaping of the pipe bowl, the grooved flange 58 finishing the top edge thereof. The parts have then assumed the position shown in Fig. 3. The material 50 quickly hardens, the foot lever is released, the mold opens by the action of the spring 87 or weighted arm or otherwise and the toy pipe is then removed from the mold.

I claim as my invention:

55 1. The combination of a sectional mold closed at one end and open at the other, a plunger smaller in diameter than the interior of the mold and provided with a flange adapted to fit within and close the open end thereof, means for closing said mold and means for inserting said plunger into the open end thereof.

2. The combination of a sectional mold closed at one end and open at the other, a 60 plunger smaller in diameter than the inter-

rior of the mold and provided with a flange adapted to fit within and close the open end thereof and having a groove on its under side, means for closing said mold and means for inserting said plunger into the open end 70 thereof.

3. The combination of a head having a mold section, a jaw hinged to said head and having, a mold section, a cam arm on said jaw, a slide frame, a plunger carried thereon, means on said slide frame for engaging said cam arm to close the mold and means for actuating said slide frame.

4. The combination of a head having a mold section, a jaw member hinged to said head and having a mold section, a cam arm on said jaw member, a slide member, a plunger carried thereby, one of said members having a beveled face adapted to engage the other member to close the mold, and means 80 for actuating said slide member.

5. The combination of a head having a mold section, a jaw member hinged to said head and having a mold section, a cam arm on said jaw member, a slide member, a plunger carried thereby, said members having 90 meeting beveled faces for engagement to close said mold, and means for actuating said slide member.

6. The combination of a head provided 95 with a mold section open at one end, a movable jaw hinged to said head and provided with a complementary mold section open at one end, a plunger carrier provided with a plunger adapted to enter the open end of 100 said mold, a slide frame connected with said plunger carrier and adapted to engage said hinged jaw, and means for actuating said slide frame, whereby the hinged jaw is 105 swung closed and the plunger inserted in succession.

7. The combination of a head having a mold section, a jaw hinged to said head and having a mold section, a cam arm adjustable on said jaw, a slide frame, a plunger carried thereon, means on said slide frame for engaging said cam arm to close the mold and means for actuating said slide frame.

8. The combination of a head having a mold section, a jaw hinged to said head and having a mold section, a cam arm on said jaw, a slide frame, a plunger carried thereon, means on said slide frame for engaging said cam arm to close the mold and a foot 115 lever for actuating said slide frame.

9. The combination of a head having a mold section a jaw hinged to said head and provided with a mold section and with lateral lugs on its opposite sides a plunger carrier having a plunger adapted to enter said mold and provided with dependent lugs adapted to engage the lugs of said hinged jaw, means for oscillating said jaw, and means for reciprocating said plunger carrier.

10. The combination of a head provided with a mold section open at one end and provided with a lateral guideway opening into said mold section near the closed end thereof, a movable jaw hinged to said head and provided with a complementary mold section open at one end and with lateral lugs on opposite sides thereof, a plunger carrier provided with a plunger and with dependent lugs engaging said jaw lugs, means for oscillating said jaw, and means for reciprocating said plunger carrier.

11. The combination of a head provided with a mold section, a lateral flaring guideway opening into said mold section, with vertical guideways and with dependent hangers, a jaw hinged to said head provided with a mold section and with a cam, a slide frame reciprocating in said guideways and provided with two cross heads one of which engages said cam, a plunger carrier supported on said frame and provided with a plunger, horizontal arms attached to said hangers, and a lever pivoted in said arms and provided with means for engaging the other crosshead for reciprocating said slide frame.

12. The combination of a head provided with a mold section, a lateral flaring guideway opening into said mold section, with vertical guideways and with dependent hangers, a jaw hinged to said head provided with a mold section and with a cam, a slide frame reciprocating in said guideways and provided with two cross heads one of which engages said cam, a plunger carrier support-

ed on said frame and provided with a plunger, horizontal arms attached to said hangers and a lever adjustably pivoted in said arms and provided with means for engaging the other cross head for reciprocating said slide frame.

13. The combination of a head provided with a mold section, a lateral flaring guideway opening into said mold section, with vertical guideways and with dependent hangers, a jaw hinged to said head provided with a mold section and with a cam, a slide frame reciprocating in said guideways and provided with two cross heads one of which engages said cam, a plunger carrier supported on said frame and provided with a plunger, horizontal arms attached to said hangers, and a lever pivoted in said arms and provided with a forked cam adapted to engage the other cross head of said frame.

14. The combination of a head having a mold section and provided with vertical guideways a movable jaw provided with a mold section, a slide frame movable in said guideways, a plunger carrier supported by said frame and provided with a plunger, springs for normally holding said plunger carrier in open position, means for closing said mold section, and means for shifting said plunger to thrust said plunger into said mold.

GEORGE H. FOX.
